CLAIM

The ornamental design for a storage track, as shown and described.

DESCRIPTION

FIG. 1 is a front perspective view of a storage track according to a first embodiment of our design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a storage track according to a second embodiment of our design;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top plan view thereof;

FIG. 14 is a bottom plan view thereof; and,

FIG. 15 is a front perspective view thereof shown in place on an unclaimed support element.

The broken lines shown in the figures represent portions of the storage track that form no part of the claimed design. The additional broken lines shown in FIG. 15 represent environment and form no part of the claimed design.
